UNITED STATES PATENT OFFICE.

WILLIAM G. EAGER, OF VALDOSTA, GEORGIA.

TACHOMETER DRIVE.

Application filed August 6, 1923. Serial No. 656,068.

To all whom it may concern:

Be it known that I, WILLIAM G. EAGER, a citizen of the United States of America, residing at Valdosta, in the county of Lowndes and State of Georgia, have invented certain new and useful Improvements in Tachometer Drives, of which the following is a specification.

My invention relates to a tachometer drive for railway cars.

The more important objects which I have in view may be briefly summarized as follows:—

1st: To improve the driving pulley applied to the car wheel axle by utilizing a split pulley having a plurality of grooves of like diameter to take care of axial movement of the axle and by providing radially adjustable centering pins which make possible its accurate concentric mounting on a tapering axle.

2nd: To provide a novel type of transmission pulley belted to the axle pulley and made up by assembling standard units of different diameter which will correspond to different diameters of the car wheels driving it, it being possible, by the use of different combinations of pulley units, to produce all of the various combination pulleys required from a minimum number of standard parts in stock.

3rd: To simplify and perfect the drive from the transmission pulley to the tachometer instrument, this being accomplished by a swiveled joint coupling of a flexible shaft to the end of the transmission pulley shaft, to the end that the drive may be installed with the least possible expense both for time and material, and with the least possible change in the railway car to which it is applied.

The advantages of my tachometer drive and the novel details of its construction, which form a part of my present invention, will all be best understood by reference to the accompanying drawings in which an illustrative embodiment of my invention is disclosed.

According to the drawings:—

Fig. 1 is a side elevation of a railway car equipped with my drive, part of the truck and part of the car body being broken away to more clearly illustrate the drive.

Fig. 2 is a plan view enlarged of the drive, as illustrated in Fig. 1. 53

Fig. 3 is a detail view of the transmission pulley shaft showing in full lines an assembly of pulley units for the medium size car wheels, the dotted lines showing pulleys which can be associated with the pulleys according to the diameters required for the larger or smaller car wheel standards. 60

Figs. 4 and 5 are end and plan views in detail of the driving pulley for the wheel axle. 63

Similar reference numerals refer to similar parts throughout the drawings.

In the embodiment of my invention illustrated, I show a railway car 1 having a truck 2, standard car wheels 3, and an axle 4 which tapers towards each end and on which the wheels 3 are mounted. All of the parts thus far described may be of any standard construction. On the axle 4 I mount a split pulley 5 having a multiple series of grooves of like diameter and having end abutting flanges 6 which are connected by bolts 7 to connect the large end of the pulley about the axle 4. At the other end of the pulley is a flange 8 extending beyond the pulley proper. I provide in this flange three radial screws 9 set approximately 120° apart on the assembled pulley and adapted to be screwed in until they engage the axle 4 and are in position to center the pulley thereon. Similar screws 10 in pairs are mounted on the flanges 6. These screws 9 and 10 thus take care of the decrease in diameter of the axle and enable the pulley to be properly centered thereon and hold it against slippage on the axle. The pulley 5 by a round steel belt or other suitable belt 11 drives the transmission pulley.

I show the transmission pulley as assembled on a shaft 12 mounted in bearings 13 suitably connected to a cross member 14 near the center of the truck overhead and on this shaft between the bearings 13 I assemble a series of pulley units selected from the series 100 15, 16, 17, 18 and 19, which have successively and uniformly decreasing diameters. The pulley units are all similarly constructed except for their differences in diameter, each having on one side an offset hub boss 20 and 105 on the opposite side a corresponding coun-

tersunk recess 21. When assembling the units the boss 20 of one will either fit into the recess 21 of the other or it can be turned to form the offset spacer hub and engage 5 the adjacent bearing 13.

Fig. 3 shows in full lines an assembly of the three medium sized pulleys 16, 17 and 18 as they would be arranged on the shaft 12. For the larger size of car wheels the 10 pulley unit 15 would be added and the unit 18 removed, the unit 17 being reversed so as to present its boss 20 in position to abut the adjacent bearing. For the smallest wheel diameters the pulley 19 would be added and 15 the pulley 16 removed. In this manner I am enabled by stocking five sizes of pulley units to build up transmission pulleys having all of the different diameters which would be required in railroad service and I thus sim- 20 plify the stocking of parts and the applica- 70 tion of the drive as much as possible. On one end of the shaft a swivel or universal drive (not shown) is mounted in an angle housing 22 and this serves to drive a chain 25 23 housed in a flexible shaft 24 and connected to the tachometer instrument 25, suit- 75 ably mounted in the car, so as to drive the rotating element thereof.

Having assembled the apparatus in the 30 manner described and having selected and mounted the appropriate group of trans- 80 mission pulleys on the shaft 12, say pulleys 16, 17 and 18, the belt 11 is applied to the pulleys 5 and 16 and the rotation thereby 35 imparted to the shaft 12 is transmitted through a small floor opening by a flexible shaft 23, 24 to the instrument, and the latter will accurately indicate the speed. In 40 rounding curves the lateral shifting move- 85 ment of the axle 4 will be cared for by the steel belt 11 slipping from one to the other of the grooves in the pulley 5, thus avoiding undue strain or wear on either of the pulleys which it connects. When the car wheel 45 wears and its tread requires to be turned down the practice is to turn it down each time one-half an inch, thereby reducing the diameter of the car wheel one inch. When

this occurs it is compensated for by shifting the belt to the next size pulley 17 and when the wheel 3 is finally turned to its smallest diameter the belt is again shifted to the pulley 18. In this way without change or adjustment the machine will always calibrate accurately. 50

Though I have described with great par- 55 ticularity the details of the embodiment of the invention herein shown, it is not to be construed that I am limited thereto, as changes in arrangement and substitution of equivalents may be made by those skilled in the art without departing from the in- 60 vention as defined in the appended claims.

Having thus described my invention, what I claim as new and desire to secure by Let- 65 ters Patent, is:—

1. In a tachometer drive, a multi-groove pulley of uniform diameter mounted on the car wheel axle, a driven pulley mounted adjacent to the truck center, a drive connecting said pulleys, and a flexible drive shaft connecting said transmission pulley and a tachometer, substantially as described. 70

2. A tachometer drive in accordance with claim 1, in which the elongated pulley on the car wheel axle is a split pulley having adjustable means to center it on the axle. 75

3. A tachometer drive in accordance with claim 1, in which the elongated pulley is a split pulley having at each end radial ad- 80 justing screws adapted to engage the car wheel axle and both center and mount the pulley thereon.

4. In a tachometer drive, the combination with a pulley driven by a car wheel axle, of a pulley shaft mounted on the truck near its pivotal center, a flexible transmission leading up through the car floor and connecting said shaft to the tachometer instrument, and a multiple pulley mounted on said shaft 90 and comprising interchangeable elements which are reversible and provided with corresponding hub bosses on one side and hub receiving sockets on the other side. 95

In testimony whereof I affix my signature. WILLIAM G. EAGER.
